ELECTRIC SWITCH OPERATING DEVICE

James O. Rexroad, Beaver, Pa., assignor to Westinghouse Electric Corporation, East Pittsburgh, Pa., a corporation of Pennsylvania

Application October 18, 1950, Serial No. 190,813

9 Claims. (Cl. 74—479)

1

My invention relates, generally, to electric switches, and, more particularly, to switches which may be operated by means of a pull-cord.

For certain applications, for example the control of conveyor belts, it is desirable to be able to turn off the power from any point along a belt. Furthermore, in such installations, it is usually desirable that the power can be turned on only from a central point.

An object of my invention, generally stated, is to provide a pull-cord operated switch which is simple and efficient in operation and which may be economically manufactured and installed.

A more specific object of my invention is to provide a pull-cord operated switch in which the actuating parts are self-returning to their normal position.

Another object of my invention is to provide a switch which may be operated by either one of two pull-cords which extend in different directions from the actuating mechanism.

A further object of my invention is to provide a switch which may be operated by either one of two actuating means.

Still another object of my invention is to provide a switch which can be operated in either one of two directions by an actuating handle and in only one direction by a pull-cord mechanism.

Other objects of my invention will be explained fully hereinafter or will be apparent to those skilled in the art.

In accordance with my invention, an enclosed switch is operated by a shaft rotatably mounted in a bushing on which a pulley is rotatably mounted. The switch may be actuated either "on" or "off" by means of a handle secured to the shaft. The switch may be actuated "off" only by either one of two ropes attached to the pulley and extending in opposite directions from the pulley which has a pin disposed therein to engage the handle. The pulley is returned to its normal position by a spring when the rope is released.

For a better understanding of the nature and objects of my invention, reference may be had to the following detailed description, taken in conjunction with the accompanying drawing, in which:

Figure 1 is a view, in plan, of an electric switch operating device embodying the principal features of my invention;

Fig. 2 is a view, partly in section and partly in side elevation of the device shown in Fig. 1;

Fig. 3 is a detailed view, in section, of the pulley for operating the switch; and

2

Fig. 4 is a view, in an end elevation, of the switch utilized in the device.

Referring to the drawing, the structure shown therein comprises a housing 10, a switch 11 disposed inside of the housing 10, a shaft 12 rotatably mounted in a bushing 13 which extends through a cover 14 for the housing 10, a pulley 15 rotatably mounted on the bushing 13 outside of the housing 10, and a handle 16 secured to the outer end of the shaft 12. The switch 11 may be attached to the base of the housing 10 by means of screws 17. The cover 14 may be attached to the housing by bolts 18.

The housing 10 shown in the drawing is of an explosion-proof type. However, housings of other types may be utilized, if desired. A bushing 19 is provided in one wall of the housing 10 through which wires may be installed for making electrical connections to the switch 11.

As shown most clearly in Fig. 4, the switch 11 may be of the single-pole double-throw type having contact arms 21 and 22 which are normally biased to the closed position by springs 23 and 24, respectively. The contact arms 21 and 22 may be actuated alternately to the open position by a cam 25 which is driven by a shaft 26.

As shown in Fig. 2, a switch handle 27 is provided for rotating the shaft 26. The shaft 12 is provided with a bifurcated end 28 which engages the switch handle 27. As previously explained, the shaft 12 is rotatably mounted in the bushing 13. The actuating handle 16 is secured to the outer end of the shaft 12, thereby providing a means for operating the switch 11 to either the "on" or the "off" position from outside the housing 10.

As explained hereinbefore, the switch 11 may be utilized to control the power supply to an electric motor which drives a conveyor belt. As also explained, it is desirable that the power to the driving motor may be turned off from any point along the conveyor. It is also desirable that the power can be turned on only from the central control station at which the switch 11 is located.

In order to accomplish the foregoing objects, the pulley 15 and pull-cords 31 and 32 are provided. The pulley 15 is rotatably mounted on the bushing 13 and is retained on the bushing 50 by a clip 33 disposed in a groove 34 in the bushing 13. The pull-cords 31 and 32 may be attached to the pulley 15 by means of pins 35 and 36, respectively. The cords extend from the pulley in opposite directions and are so connected to the pulley that it can be rotated in one direction

only by pulling either one of the cords which extend along the conveyor belt (not shown). The pulley is returned to the position shown in the drawing by means of a spring 37 having one end 38 attached to the cover 14 and the other end 39 attached to the pulley 15.

A pin 41 is secured to one side of the pulley 15 and is disposed to engage the actuating handle 16 to rotate the shaft 12 when either one of the cords 31 or 32 is pulled, thereby operating the switch 11 to the "off" position. When the pull cord is released, the pulley is returned to its normal position by the spring 37. However, the switch 11 remains in the "off" position until the handle 16 is operated manually to reclose the switch. Thus, it is necessary for the operator to be at the control station to start the conveyor belt.

As shown, stop pins 42 and 43 are secured to one side of the pulley 15 and are disposed to engage a stop pin 44 in the cover 14 to limit the travel of the pulley 15 and protect the switch 11 from damage by overtravel of the pulley 15. Eye-bolts 45 and 46 may be attached to the cover 14 to guide the pull-cords 31 and 32, respectively.

A groove pin 47 provided in the cover 14 functions as a guide pin for the bushing 13 to ensure the proper positioning of a name plate 48 on the clip 33 which is attached to the bushing 13. The pin 47 also prevents rotation of the bushing 13 in the cover 14. While the pulley 15 has been shown as being suitable for operating the switch only from "on" to the "off" position, it will be understood that it could be constructed to turn the switch from the "off" to the "on" position, if desired.

From the foregoing, it is apparent that I have provided a device suitable for remotely operating a control switch from any point along a conveyor belt or similar apparatus. The operating device herein disclosed may also be utilized for other applications requiring operation of a switch from remote points, as well as from the point at which the switch itself is located. The operating device is simple and rugged in construction, thereby making it particularly suitable for application in mines or other places where it may be subjected to rough treatment.

Since numerous changes may be made in the above described construction, and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. In an operating device for a switch having an actuating member, in combination, a rotatable shaft for operating said member, a handle secured to the shaft for actuating the shaft in either direction, a pulley rotatable about the shaft, actuating means secured to the pulley to engage said handle when the pulley is rotated in one direction only, means for securing pull-cords which extend from the pulley in opposite directions to the pulley to rotate it in said one direction, and spring means for biasing the pulley in the other direction independently of said handle.

2. In an operating device for a switch having an actuating member, in combination, a rotatable shaft for operating said member, a handle secured to the shaft for actuating the shaft in either direction, actuating means rotatable about

the shaft to engage handle when the actuating means is rotated in one direction only, means for attaching pull-cords which extend from the actuating means in opposite directions to the actuating means to rotate it in said one direction, spring means for biasing the actuating means in the other direction independently of said handle, and stop means for limiting the rotation of the actuating means.

3. In an operating device for a switch having an actuating member, in combination, a rotatable shaft for operating said member, a handle attached to the shaft for actuating the shaft in either direction, a pulley rotatable about the shaft, actuating means secured to the pulley to engage said handle when the pulley is rotated in one direction only, means for attaching pull-cords which extend from the pulley in opposite directions to the pulley to rotate it in said one direction, said handle being free to rotate the shaft independently of the pulley, and stop means for limiting the rotation of the pulley, said pulley being rotatable in the other direction without operating the actuating member.

4. In an operating structure for a switch disposed in a housing and having an actuating member, in combination, a shaft rotatably mounted in a wall of the housing with its inner end engaging the actuating member, a handle secured to the outer end of the shaft to rotate it in either direction, a pulley rotatable about the shaft, a pin secured to the pulley to engage said handle when the pulley is rotated in one direction only, and means for attaching a pull-cord to the pulley for rotating the pulley in said one direction, said pulley being rotatable in the other direction without operating the actuating member.

5. In an operating structure for a switch disposed in a housing and having an actuating member, in combination, a bushing extending through a wall of the housing, a shaft rotatably mounted in the bushing and having its inner end engaging the actuating member, a handle secured to the outer end of the shaft to rotate it in either direction, a pulley rotatably mounted on the bushing, a pin secured to one side of the pulley to engage said handle when the pulley is rotated in one direction only, and means for attaching pull-cords which extend from the pulley in opposite directions to the pulley to rotate it in said one direction, said pulley being rotatable in the other direction without operating the actuating member.

6. In an operating structure for a switch disposed in a housing and having an actuating member, in combination, a bushing extending through a wall of the housing, a shaft rotatably mounted in the bushing and having its inner end engaging the actuating member, a handle secured to the outer end of the shaft to rotate it in either direction, a pulley rotatably mounted on the bushing, a pin secured to one side of the pulley to engage said handle when the pulley is rotated in one direction only, means for attaching a pull-cord to the pulley to rotate it in said one direction, and spring means for biasing the pulley in the other direction, said pulley being rotatable in the other direction without operating the actuating member.

7. In an operating structure for a switch disposed in a housing and having an actuating member, in combination, a bushing extending through a wall of the housing, a shaft rotatably mounted in the bushing and having its inner end engaging the actuating member, a handle secured to the

outer end of the shaft to rotate the shaft in either direction, a pulley rotatably mounted on the bushing, a pin secured to one side of the pulley to engage said handle when the pulley is rotated in one direction only, and means for attaching pull-cords which extend from the pulley in opposite directions to the pulley to rotate it in said one direction, said handle being free to rotate the shaft independently of the pulley, said pulley being rotatable in the other direction without operating the actuating member.

8. In an operating structure for a switch disposed in a housing and having an actuating member, in combination, a bushing extending through a wall of the housing, a shaft rotatably mounted in the bushing and having a bifurcated inner end engaging the actuating member, a handle secured to the outer end of the shaft to rotate the shaft in either direction, actuating means rotatably mounted on the bushing to engage said handle when the actuating means is rotated in one direction only, means for attaching a pull-cord to the actuating means to rotate it in said one direction, spring means for biasing the actuating means in the other direction independently of the handle, and stop means for limiting the rotation of the actuating means.

9. In an operating structure for a switch disposed in a housing and having an actuating member, in combination, a bushing extending through a wall of the housing, a shaft rotatably mounted in the bushing and having a bifurcated inner

end engaging the actuating member, a handle secured to the outer end of the shaft to rotate it in either direction, a pulley rotatably mounted on the bushing, a pin secured to one side of the pulley to engage said handle when the pulley is rotated in one direction only, means for attaching pull-cords which extend from the pulley in opposite directions to the pulley to rotate it in said one direction, spring means for biasing the pulley in the other direction independently of the handle, said handle being free to rotate the shaft independently of the pulley, and stop means for limiting the rotation of the pulley.
